UNITED STATES PATENT OFFICE.

FRANK ORTH, OF INDIANA HARBOR, INDIANA.

REGENERATOR CONSTRUCTION.

1,207,616.

Specification of Letters Patent.

Patented Dec. 5, 1916.

Application filed October 4, 1915, Serial No. 54,051. Renewed October 21, 1916. Serial No. 127,037.

To all whom it may concern:

Be it known that I, FRANK ORTH, a citizen of the United States, residing at Indiana Harbor, county of Lake, and State of Indiana, have invented certain new and useful Improvements in Regenerator Constructions, of which the following is a specification.

This invention has reference to certain improvements in regenerator constructions.

The features of invention herein disclosed are particularly intended for use in regenerators for furnaces, such as open-hearth furnaces or the like, but said features can also be used to advantage in regenerators for many other classes of service.

In the ordinary type of regenerator construction, considerable difficulty is experienced in securing a uniform distribution of the gases over the entire body of the heat absorbing material, with the result that the material in some portions of the construction is worked at a higher degree of heat absorbing economy than in other portions. The usual experience is that during the heating of the regenerator by the hot gases from the furnace, said gases will tend to remain in the upper portion of the regenerator chamber during their travel throughout the length of said chamber, and will only descend and pass out through the body of the heat absorbing material as they approach the back end of the chamber. This tendency is experienced because of the fact that the hot gases tend to maintain a higher elevation in the chamber than the relatively cooler gases. It is likewise found that on the other half of the cycle, the incoming cold air will tend to flow along the bottom portion of the chamber until it reaches a point adjacent to the front end of the chamber, at which point it will rise through the checker work and then pass into the flue. This tendency is experienced by reason of the fact that the cold gases will remain at a relatively low position as long as possible. It is thus seen that during the heating portion of the cycle, the back end of the mass of heat absorbing material will be heated more than the front end of said mass, and that on the cooling portion of the cycle, the greatest portion of the air will pass through the front portion of the heat absorbing mass. It thus appears that not only is the heating effect uneven in the different

air does not tend to pass through the hottest portion of said unevenly heated mass.

One of the objects of the present invention is to so construct the mass of heat absorbing material so that there will be a tendency 60 to secure a more even distribution of the hot gas during the heating portion of the cycle, and to secure a more even passage of the air during the cooling portion of the cycle.

In this connection another object of the 65 invention is to so construct the heat absorbing mass that a maximum amount of heat absorbing material may be placed within in a chamber of given size.

In this connection still another object is 70 to so arrange the construction that the absorbing material embodying the features of the present invention may be readily built into a shell or chamber of the usual or customary form, thus making it possible to secure the benefits of the present invention 75 without necessitating complete reconstruction of the old style of regenerator chamber.

Other objects and uses of the invention will appear from a detailed description of 80 the same, which consists in the features of construction and combination of parts, hereinafter described and claimed.

Referring to the drawings—Figure 1 shows a vertical longitudinal section through 85 the body of a regenerator construction, having applied thereto one embodiment of the features of my invention; Fig. 2 is a horizontal section taken on the line 2—2 of Fig. 1, looking in the direction of the arrows; Fig. 3 is a vertical cross-section taken on the line 3—3 of Fig. 2, looking in the direction of the arrows; Fig. 4 is a vertical longitudinal section through a modified construction of regenerator, also embodying the features of the present invention; and Fig. 5 is a vertical cross-section taken on the line 95 5—5 of Fig. 4, looking in the direction of the arrows.

I will first describe the construction shown 100 in Figs. 1, 2 and 3. In this case the chamber is designated in its entirety by numeral 6. The flue leading to the furnace is designated by the numeral 7 and the discharge connection by the numeral 8. The lower 105 portion of the heat absorbing material comprises ordinary checker work 9, or any other suitable form of heat absorbing material, supported by cross riders 10, which in turn are mounted on the rider walls 11. 110

Between the rider walls 11, are the passages 12, which lead into the discharge opening 8, which also communicate with the bottom of the mass of heat absorbing material. Ordinarily the features of the present invention are applied to the upper portion of the heat absorbing material. In the present case, said upper portion comprises a plurality of longitudinal separated walls 13 and a plurality of pavements or partitions built into and between said walls. In the arrangement now being considered, these partitions serve the double function of providing dust-catching pockets, and of also controlling the passage of the air and gases through the different portions of the heat absorbing material, so as to secure the uniform distribution previously referred to. In the particular arrangement illustrated, the partitions are of two classes, some of them being horizontal and some of them vertical. The horizontal partitions are designated by the numeral 14 and the vertical partitions by the numeral 15. The partitions 15 extend a desired distance above the partitions 14, so as to establish dust-catching pockets, and they extend down into the body of the heat absorbing material a distance sufficient to give the desired uniform gas distribution. If desired, there may also be provided across the front end of each partition 14, a tongue or the like 16, so as to improve the form of the dust-catching pocket, and there may also be provided beneath the front end of each of the horizontal partitions a plurality of supporting tiles 17. The walls 13 will ordinarily be placed as close together as possible, to secure the desired regenerator capacity, while at the same time permitting a free passage of the gases between said walls. However, at points between the adjacent edges of consecutive partitions 14, I may leave out portions of selected ones of the walls 13, so as to provide the vertical flues or the like 18, best shown in Fig. 2. In the particular arrangement illustrated, the flues 18 are formed by leaving out portions of alternate walls 13, but manifestly said flues may be either larger or smaller than the sizes as thus determined. Furthermore, as shown in Fig. 1, the enlarged flues 18 not only extend downward past the partitions 14, but also extend horizontally beneath the partitions 14 for a distance of substantially equal to one-half the length of said partitions, thereby providing the horizontal passages 19. These horizontal passages will insure a more uniform and perfect delivery of the gases into the body of the heat absorbing material 9. If desired, the doors or ports 20 may be formed in the side walls of the chamber opposite to the partitions 14, so as to facilitate removal of dust from said partitions. It will

be observed from examination of Fig. 1 that the partitions 15 extend down substantially to the heat absorbing material 9. These partitions constitute in effect baffles to effectively control the passage of the air and gas through the body of the material and thus assist in securing the aforementioned uniform distribution. By regulating the sizes of the flues 18 and 19 in the different portions of the structure, the certainty of uniform distribution can be still further advanced.

Considering now the arrangement shown in Figs. 4 and 5, in this case the upper portion of the heat absorbing material also comprises a series of parallel walls between which gases pass in finding their way into the body of the heat absorbing material, but in this case said walls extend across the chamber instead of lengthwise thereof. These are the walls 21 and 22. The walls 21 are for the most part carried by a plurality of riders 23, which in turn are supported by the body of heat absorbing material 9. Between the riders 23 are the flue openings 24, and as shown in Fig. 4, said flue openings may be carried down as far as may be desired, into the body of heat absorbing material 9. Extending lengthwise in the upper portion of the structure, is a channel or the like 25, by means of which the gases are delivered to the spaces between the various cross walls 21 and 22. Said channel extends down to a point near the body of heat absorbing material 9, where there is located a pavement or trough 26. This pavement is in turn carried by the lower portions of the walls 21, and also by additional or intermediate shallow cross walls 27, which are set in between the lower portions of the walls 21. In addition to the foregoing a central partition 28 may be run up into contact with the lower portion of the trough 26, so as to more perfectly divide the stream of gases to the two sides of said trough. The trough may also be provided with the side walls 29 and 30. Across the upper portions of the partitions 21 there may be supported the pavements 31 and 32, and the cross walls 22 may be carried by said pavements. These walls 22 may be built up much higher into the upper portion of the chamber than the ordinary heat absorbing material construction, so that in this way a substantial increase in regenerator capacity may be secured within a chamber of given size.

While I have herein shown and described only two constructions embodying the features of my invention, still it will be understood that I am in no wise limited to said constructions, but include within the scope of my invention other equivalent constructions, operating in equivalent manners to produce equivalent results.

I claim:

1. In a regenerator the combination with an inclosing chamber, of a suitable heat absorbing structure within the same, a plurality of cross walls mounted on the upper portion of said structure, the central portions of said cross walls being of lesser elevation than their side portions, whereby there is provided a longitudinally extending channel 10 through said cross walls, and a trough laid in the lower portion of said channel.
2. In a regenerator the combination with a chamber, of a suitable heat absorbing structure within the same, a plurality of cross walls on the upper portion of said structure, the central portions of said cross walls being of lesser elevation than their side portions to provide a longitudinally extending channel through said cross walls, 15 a suitable pavement on the lower portion of said channel, other pavements on the side portions of the cross walls, and partitions supported by said last named pavements.
3. In a regenerator the combination with an inclosing chamber, of a suitable heat absorbing structure within the lower portion of the same, and a plurality of cross walls mounted on the upper portion of said heat absorbing structure, the central portions of 20 said cross walls being of lesser elevation than their side portions to thereby provide a longitudinally extending channel through the cross walls, and the adjacent cross walls being separated from each other to provide 25 continuous open slots leading from said channel to all portions of the said heat absorbing structure, and each cross wall having a maximum thickness not greater than one dimension of the blocks from which it 30 is constructed.
4. In a regenerator the combination with an inclosing chamber, of a suitable heat absorbing structure within the same, a plu- 35

- rality of parallel walls mounted on the upper portion of said structure and serving to provide between them a plurality of parallel vertically extending passages for the travel of gas into or away from the lower portion of the heat absorbing structure, and cross partitions between said walls located below the upper edges of the walls, the walls above said cross partitions being unconnected.
5. In a regenerator the combination with an inclosing chamber, of a suitable heat absorbing structure within the same, a plurality of substantially parallel vertical walls mounted on the upper portion of said structure and serving to provide between them a plurality of substantially parallel vertically extending passages, having their lower ends in communication with the lower portion of the heat absorbing structure, and cross partitions between said walls located below the upper edges of the walls, the walls above said cross partitions being unconnected.
6. In a regenerator the combination with an inclosing chamber, of a suitable heat absorbing structure within the same, a plurality of substantially parallel vertical walls mounted on said heat absorbing structure, and serving to provide between them a plurality of substantially parallel vertically extending passages, having their lower ends in communication with the lower portion of the heat absorbing structure, and suitable partitions extending between said walls for the purpose of guiding the gases in their flow to and from the walls, said partitions being located below the upper edges of the walls, and the walls above said partitions being unconnected.

FRANK ORTH.
